BALING PRESS

Ivan Z. Martin, Ephrata, Pa., assignor of one-half to Noah N. Burkholder, Ephrata, Pa.

Application December 8, 1941, Serial No. 422,144

9 Claims. (Cl. 100—25)

This invention relates to baling presses and more especially to the means employed for placing under compression the material to be baled.

An object of the invention is to provide a compressing head mounted in a new and novel manner whereby the continuous rotation of a drive shaft will produce a combined oscillating and sliding motion of the head with the result that material supplied to the press will be directed into and compressed within the baling chamber.

A further object is to provide mechanism of this character which operates to speed up the baling operation and materially reduces the power required to form a bale.

Another object is to provide baling mechanism which is durable and compact in construction and formed of few parts.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawings

Figure 1 is a central, vertical, longitudinal section through that portion of a baling press constituting the present invention.

Figure 2 is a top plan view thereof.

Figure 3 is a section on line 3—3, Figure 1.

Figure 4 is a section on line 4—4, Figure 1, but showing the compressing head in the dotted line position illustrated in Figure 1.

Referring to the figures by characters of reference, 1 designates the baling chamber of the press, the same being extended from but opening into a substantially cylindrical intermediate chamber 2 into which opens a feed chamber 3, the latter chamber and the baling chamber 1 being preferably coaxial as shown particularly in Figure 1.

Oppositely extending aligned bearing studs 4 are carried by the side walls of the intermediate chamber 2 at the centers thereof and mounted for rotation on these studs are wheels 5 connected by a cross-rod 6. In order that the movement of this rod during back and forth rotation of the wheels 5 may not be interfered with, an arcuate slot 7 is formed in each side wall of the intermediate chamber 2. The length of each

slot is equal to the length of the path of movement of the rod 6.

Each of the wheels 5 carries an arcuate series of teeth 8 in the form of regularly spaced pins and meshing with the pins of the respective series are gears 9 rotatable with a transverse shaft 10. This shaft is journaled in slides 11 mounted for up and down movement within guides 12 mounted upon the top of chamber 2. A pulley 13 can be secured to shaft 10 so as to receive motion from any suitable source through a belt 14. The guides 12 and the slides 11 are so proportioned that when the slides are in their lowermost positions, the gears 9 will be positioned where they can rotate beneath the engaged pins 8 whereas, when the slides are raised, the gears 9 will be supported on the pins 8 while meshing therewith. Thus when the gears 9 are rotated continuously in one direction as indicated, for example, by the arrow in Figure 1, they will drive the wheels 5 in a counter-clockwise direction until the pins at one end of the series reach positions beneath the shaft 10. Thereafter the shaft and the gears 9 will drop to their lower positions and the continued rotation of the gears will result in said gears driving the teeth in a clockwise direction until the teeth at the other ends of the two series are reached whereupon gears 9 will move upwardly around said end teeth and reassume raised positions. This, obviously, will result again in driving the wheels in a counter-clockwise direction. Thus as the gears 9 continuously rotate in one direction, the wheels 5 will be rotated back and forth, the distance of movement being such as to cause rod 6 to move within the slots 7 from one end to the other of the slots.

Located at the sides of the intermediate chamber 2 adjacent to the inlet end 14 of the baling chamber 1 are forked guides in the form of arcuate channels 15 or the like which diverge upwardly and downwardly toward the top and bottom of the inlet 14 from intermediate pockets 16 which are positioned in the same horizontal plane with the axis of rotation of wheels 5 and with the longitudinal centers of the chambers 1 and 3. Mounted in these guides are anti-friction rollers 17 carried by the sides of the compressing head 18 adjacent to one end thereof, the opposite end portion of this head being connected to and movable with the rod 6. As shown particularly in the drawings the compressing head 18 has its opposite faces flat, one being a duplicate of the other and the head is so proportioned that when the antifriction rollers 17 are located

in one end of the guide 15, the rod 6 carrying the other end of the head will be so positioned that the head will bridge and be supported close to the inlet end 14 of the baling chamber 1.

That end of the head 18 connected to the rod 6 has a shearing blade 19 connected thereto, said blade being provided with oppositely disposed cutting edges 20. These edges are adapted to cooperate with cutting edges 21 of blades 22 which are secured to opposed walls of the feed chamber 3 and can be adjustably mounted if so desired.

Assuming that the shaft 10 is rotating continuously in the direction of the arrow shown in Figure 1 and the parts are positioned as shown by full lines in said figure, it will be apparent that further rotation of said shaft will result in the gears 9 moving past the engaged pins 8 so that the gears thus will drop to their lower positions while remaining in mesh with the adjacent pins. Further rotation of the shaft and gears will result in rotation of the wheels 5 in a clockwise direction. If material to be baled has been supplied to the intermediate chamber from the feed chamber 3, the rotation of the wheels 5 in a clockwise direction will result in rod 6 moving away from the position shown by full lines in Fig. 1 and along the slots 7, dragging with it the compressing head 18. This will result in the head sweeping up all of the material in the path thereof and at the same time pulling the antifriction rollers 17 along the upper portions of the guides 15 into the pockets 16. The advancing cutting edge 20 of the blade 19 will cooperate with the cutting edge 21 at the top of the chamber 3 to shear off any material which may be extended outwardly past the blade 19. When rod 6 reaches the horizontal plane occupied by the axis of rotation of wheels 5 and begins to move upwardly from said plane, rod 6, as it moves toward the upper end of the slot 7, will thrust the head 18 so that the antifriction rollers 17 will move downwardly toward the lower ends of the guides 15 until rod 6 reaches the upper end of slots 7 whereupon the head 18 will have been brought into position across the inlet 14 of chamber 1 with rod 6 uppermost and rollers 17 lowermost. While moving to this position the head forces into chamber 1 all of the material in the path thereof and during such movement additional material to be baled can be fed into chamber 2 from the feed chamber 3 where it will occupy the space back of head 18. As soon as the rod 6 reaches the upper ends of slots 7, gears 9 reach one end of the series of pin-teeth 8 and ride around the same to assume a position above the path of movement of the pin-teeth. Thus continued rotation of shaft 10 will result in moving the wheels 5 in a counter-clockwise direction and, as a result, the rod 6 will move away from the upper ends of slots 7, pulling the head 18 therewith until the antifriction rollers are raised into the pockets 16. As rod 6 moves downwardly past the longitudinal center of the press it will exert an upward thrust against head 18, causing the rollers 17 to move upwardly within the guides until the head is returned to the position shown by full lines in Figure 1. Consequently the material previously deposited back of the head will be forcibly expelled through inlet 14 into the baling chamber 1. Thereafter the operation already described will be repeated, the wheels 5 rotating back and forth and causing the head 18 to swing and slide to the two positions described so as to

produce successive compressing operations. As the head 18 is used for pressing material forwardly into the baling chamber 1, it will be apparent that the resistance of this material against the forward movement of the head 18 is sufficient to prevent the head from falling forwardly and becoming entangled in the guides. As the head cannot fall forwardly when the rollers reach the intermediate positions and 10 start moving upwardly therefrom, said rollers must of necessity travel upwardly along the convex walls of the upper portions of the guides.

Obviously every time the head is moved in a direction to force material in the path thereof, 15 one of the cutting edges 20 will engage one of the cutting edges 21 to shear off the material in the path thereof.

It is to be understood of course that the construction of the baling press can be modified as 20 desired without departing from the spirit of the invention as claimed and while slots 7 have been shown to permit movement of the rod 6, it will be understood of course that any clearance permitting such movement may be employed.

25 Importance is attached to the fact that the head 18 constitutes both a sweep and a compressor, each operation of the head serving to sweep material from the chamber 2 into the inlet 14 and the two faces of the head being brought successively into compressing position.

What is claimed is:

1. In a baling press the combination with a baling chamber, a feed chamber, and an intermediate chamber, of a compressing head movably mounted within the intermediate chamber, means coupled to one end portion of the head for moving said end portion along an arcuate path into position adjacent to either of two opposed walls of the baling chamber, and cooperating means in the intermediate chamber and on the head for guiding the other end of said head toward the other one of said opposed walls.

2. In a baling press a baling chamber having an inlet, a compressing head movably mounted adjacent to the inlet, means connected to one end of the head for moving said end along an arcuate path toward either of two opposed walls of the inlet and separate means upon and cooperating with the head for guiding the other end of said head during the said movement toward the other one of said opposed walls of the inlet thereby to position the head across the inlet.

3. In a baling press a baling chamber having an inlet, a material-holding chamber opening into said inlet, a compressing head movably mounted within said material-holding chamber, means connected to one end of the compressing head for moving said end in an arc within said chamber into position adjacent to either one of two opposed walls of the inlet, and cooperating means adjacent to and upon the head for guiding the other end of said head toward the other one of said opposed walls of the inlet, thereby to sweep material into the baling chamber from the other chamber and compress it within the baling chamber.

4. In a baling press the combination with a baling chamber having an inlet and a second chamber opening thereinto, of a combined sweep and compressing head mounted to slide and swing within said second chamber, oscillating means for actuating said head to sweep material from said second chamber and compress it within the baling chamber, guides on the wall of the second chamber, and means on the head and

cooperating with the guides for reversing the head during the movement of said oscillating means in each direction.

5. In a baling press the combination with a baling chamber having an inlet and a second chamber opening thereinto, of a combined sweep and compressing head mounted to slide and swing within said second chamber, and means for actuating said head to sweep material from said second chamber and compress it within the baling chamber, said means including a wheel mounted for back and forth rotation, continuously rotating means for actuating the wheel, means for coupling the wheel to one end portion of the head, forked guides adjacent to the inlet, and means carried by the other end of the head for sliding movement within the guides.

6. In a baling press the combination with a baling chamber having an inlet and a second chamber opening thereinto, of a combined sweep and compressing head mounted to slide and swing within said second chamber, and means for actuating said head to sweep material from said second chamber and compress it within the baling chamber, said means including opposed interrupted pin-tooth gears, driving gears meshing therewith and mounted for radial movement relative thereto, said gears being rotatable in one direction to impart an oscillating movement to the pin-tooth gears, a connection between the gears constituting a support for one end of the head, forked guides adjacent to the inlet extended toward opposed walls of the inlet, and means carried by the other end of the head for movement within the guides.

7. In a baling press a baling chamber having an inlet, a second chamber opening thereinto and having an inlet for material to be baled, a combined sweep and compressing head movably mounted within said second chamber, means for

oscillating one end portion of the head within said second chamber and for imparting a sliding movement thereto, forked guides each diverging toward opposed walls of the inlet, and means carried by the other end of the head for movement within the guides.

8. In a baling press a baling chamber having an inlet, a second chamber opening into the inlet and having an inlet for material to be baled, a combined sweep and compressing head movably mounted within said second chamber, opposed guides each having diverging portions extended toward opposed walls of the inlet of the baling chamber, means carried by one end portion of the head for movement within the guides, and means operatively connected to the other end of the head for sliding and swinging the head relative to the guides thereby to sweep material from said second chamber into the baling chamber and compress the material in the baling chamber.

9. In a baling press a baling chamber having an inlet, a second chamber opening into the inlet and having an inlet for receiving material to be baled, a reversible sweep and compressing head movably mounted within said second chamber, opposed guides each diverging toward opposed walls respectively of the inlet of the baling chamber, each of said guides having an intermediate pocket, means carried by the head at one end for movement along the guides, oscillating driving means, and a connection between said driving means and the other end of the head positioned to successively pull and push the head during each movement of said oscillating means, thereby to sweep material from the path of the head toward the inlet of the baling chamber, reverse the head, and compress the material within the baling chamber.
